QUADRUPLEX TELEGRAPH SYSTEM.

1,109,830.

Specification of Letters Patent.

Patented Sept. 8, 1914.

Application filed May 9, 1912. Serial No. 696,162.

To all whom it may concern:

Be it known that I, JOHN GOTT, a subject of the King of Great Britain, and resident of Hove, Brighton, England, have invented 5 certain new and useful Improvements in Quadruplex Telegraph Systems, of which the following is a specification.

It has been the common practice since the introduction of quadruplex working on telegraph lines to employ what is called a "neutral" or non-polarized relay, the purpose of which is to give a signal in the same direction, whatever be the polarity of the signaling current. Theoretically it is held to be immaterial whether the arriving current from 10 the distant end of the line be positive or negative, the relay acting in the same direction for either current. It was, however, observed from the first, that during the instant the sending currents were reversed at the distant end of the line the non-polarized relay would open the contacts and thus break the signal which was being received. This defect in the neutral relay has rendered 15 it necessary to apply various means and devices for continuing the signal, or to bridge such breaks. The neutral or non-polarized relay has always been the weak side of a quadruplex apparatus and the various quadruplex systems in use differ almost solely in 20 the means for overcoming this defect or weakness in the system.

It is the object of this invention to entirely dispense with the neutral relay and to 25 substitute therefor a double, differentially wound polarized relay, and to so arrange said relay that a signal will be produced without regard to the polarity of the line current, the coils of said relay responding to 30 the increased current on the line and not being affected by the weaker normal current.

The signal transmitting devices used with 35 this invention may be any of the well-known forms used in quadruplex apparatus; and the ordinary polarized relay is to be used as it is now arranged in such systems.

By dispensing with the "neutral" or non-polarized relay and substituting therefor the double polarized relay, the operation of 40 the signal receiving devices depends solely upon the reversals of the line current, the double polarized relay responding only to the increased current, as will be hereinafter described. By this means a very positively 45 acting apparatus is secured wherein the

chattering or breaks in the signals received on the neutral relay of the old form of apparatus is avoided.

The drawing is a diagrammatic representation of a quadruplex telegraph system 60 with the invention applied thereto.

Referring to the various parts by numerals, 1 and 2 designate the current generators, the positive side of 1 and the negative side of 2 being connected to the stops 4 of the pole changer 5. The pole changer is operated through the key 6 (usually known as the "A" key or "A" side) in the usual manner to put normal positive or negative current to the line, the armature of said pole 65 changer being connected to the line in the usual manner.

The transmitter 7 is arranged in the usual manner to increase and decrease the current on the line, said transmitter being operated 70 by the key 8 (usually called the "B" key or "B" side). The armatures of the pole changer and of the transmitter are connected together by a conductor and in said conductor is arranged a resistance 10. 75

11 designates the back stop of the transmitter 7. The current from the armature of the transmitter is split at 13 in the usual manner in quadruplex apparatus and is carried through the polarized relays, which 80 constitute the receiving instruments in this apparatus, one side going to the main line and the other portion going to the artificial line. The artificial line may be made up in any desired manner and provided with 85 means whereby it may be balanced with the main line.

The single polarized relay 14 is responsive in the usual manner to the impulses of normal current sent by "A" key through the 90 pole changer at the distant end of the line and operates precisely as in the systems now commonly used.

A double polarized relay 15 is substituted 95 for and takes the place of the old and well-known "neutral" relay, and responds to the increased current of both polarities, one of its coils responding to current of one polarity, the other responding to current of opposite polarity. This double relay consists 100 of two coils 17 and 18 with their armatures 17' and 18'. Armature 17' normally rests against a back contact 17'', and armature 18' normally rests against a back contact 18''. These coils are differentially wound, 110

and their windings are so arranged that the armature of the coil 17 will be withdrawn from its back contact when current of positive polarity flows through the said coil; and the coil 18 is wound so that when a current of negative polarity flows therethrough its armature will be drawn from its back contact 18''. It will, of course, be understood that this arrangement of the coils may be reversed, if desired. The armature 18' is electrically connected to the back contact 17''; and the back contact 18'' is electrically connected through a resistance 19 and galvanometer 20 to a battery 21. The armature 17' is also in circuit with said battery. It is manifest, therefore, that when the armatures of both coils 17 and 18 are against their back contacts the local battery circuit is closed and that when either one of said armatures is withdrawn from its back contact the said circuit is open. A relay 22 is arranged in the local circuit in such manner that when the armatures 17' and 18' are against their back contacts, said relay is short circuited; but when the current is opened by either of the said armatures leaving its back contact the circuit will then be shunted through said relay and a signal will be given. The relay 22 may be arranged to close a circuit for a sounder or other instrument.

The coils 17 and 18 are rendered insensitive or unresponsive to the "A" or normal currents in any suitable manner, for instance, they may be so wound as to act only when the increased current is used, the single polarized relay at all times responding to said "A" or normal currents. When the "B" key is held down at the distant end and the "A" key at the same end makes a reversal of line current the armature of either the relay 17 or 18, whichever is against its back contact, will swing to its front contact, and the armature of the other relay will leave its front contact and will swing to its back contact. The armature leaving its back contact in response to the reversed current will possibly lag or move more slowly than the other armature in leaving its front contact this latter beginning its movement the instant the circuit is broken. It thus might happen that the receiving instrument in the local circuit controlled by the two coils of the double relay would be short-circuited, and the signal arriving from the "B" key interrupted or broken. To provide against this and to insure a simultaneous reversal of the positions of the two armatures of the double polarized relay, I use a transformer so connected that as the armature of each of the relays goes over against its front contact it sends a current through the connected primary coil, thereby inducing a current in the secondary coil which coil is joined across the line terminals

of the two coils of the relay. The action of this induced current is, first, to hold the armature of one coil against its back contact and the armature of the other coil against its front contact. When the armature which is against its front contact, and which completes the local circuit through the primary coil of the transformer, is released and said circuit is broken, the current induced in the secondary of the transformer tends to reverse the position of the other armature of the double relay, so that the instant of no current in the line from the distant end is bridged over by this induced current and the said armature is tending to respond to the reversed current before said current is on the line at the distant end. The armature of the second relay is, therefore, in a condition to respond promptly to the reversed currents from the distant end, and there will be no lag in the movement of the armature of the said second relay. To accomplish this result a transformer having two primary windings 23 and 24 and a single secondary winding 25 is employed. The armature 17' is electrically connected to coil 23 and said coil is connected to a battery 27 through a resistance 26, said battery being connected to the front contact of relay 17. The other primary winding 24 is similarly connected to the armature 18' of the relay 18 and to the front stop thereof through a resistance 28 and battery 29. The secondary winding is connected through a variable resistance to the main line side of the relay coils 17 and 18. High resistance coils 31 are connected to the batteries 27 and 29 and to the transformer coils 23 and 24 to serve as anti-sparking shunts during the breaking of the circuits between the armatures 17' and 18' and their back contacts.

It is manifest that when the armature 17' is moved to its front contact the circuit through coil 23 and the battery 27 is complete. This will induce a current in the secondary coil tending to hold the armature 17' against its front contact and the armature 18' against its back contact 18''. When the armature 17' leaves its front contact the circuit through the coil 23 will be broken, thereby inducing a current in the secondary 25 which will tend to swing the armature 18' from its back contact and toward its front contact. The result is that the armatures are ready to respond promptly to the reversals of current at the distant end of the line, and as hereinbefore stated, the period of no current on the line from the distant end is bridged by this induced current which induced current is opposite in polarity to the interrupted line current.

It is manifest that should the armature 17' arrive at its back contact before the armature 18' leaves its back contact the receiving instrument in the local circuit con-

trolled by the double polarized relay would be short circuited, and the arriving signal interrupted. By arranging the transformer coils as described this is effectually prevented and upon a reversal of current at the distant end when the "B" key is down or closed, the armature of the relay which is against its back contact will leave said contact before the other armature has reached its back contact. This action, of course, will take place with respect to each of the armatures without regard to which one is against its front contact.

It will, of course, be understood that the primary coils of the transformer are to be so connected and arranged that their influence on the relay coils is opposite to each other. It is also manifest that the resistance of the secondary coil with the added resistance is so high that it does not interfere with the working of the relays on which it is a shunt.

It is clear that the high capacity and retardation of underground and submarine lines is met or neutralized by this method of injecting, so to speak, into the line at the receiving end, automatically, and at the required instant, the current which is missing at the time of the reversal at the sending end. This is a very important feature of the invention and prevents any possibility of ragged or indistinct signals from the double polarized relay.

The operation of the apparatus will be obvious to those skilled in the art but may be briefly described as follows: The single polarized relay responds to the operation of the pole changer or "A" key of the transmitting apparatus, the double polarized relay remaining unresponsive to those changes in polarity of the normal line current. When, however, the transmitter, or the "B" key of the transmitting apparatus is operated the increased current to the line will operate one or the other of the polarized relays constituting the "B" current receiving means, current of one polarity moving the armature of coil 18 to open the relay shunt and thereby produce a signal through the said relay. A current of opposite polarity from the "B" key of the sending apparatus will operate to withdraw the armature from its back contact and thereby again open the relay shunt circuit and cause said relay to be operated by the battery current. It will, therefore, be seen that the pair of polarized relays of the second or B-side of the apparatus will respond to currents of both polarities but only when the increased current is on the line through the operation of the "B" key or transmitter at the distant end.

It is manifest that the double relay constitutes a receiving instrument which is actuated by electric currents of opposite po-

larity, and that through its control of a local circuit containing an ordinary relay, reproduces said impulses in a local circuit as impulses of like polarity. As used in a quadruplex system it forms an efficient substitute for the old neutral relay and eliminates all of the difficulties inherent in that old form of apparatus. It strengthens the quadruplex system in such manner as to make both sides of the system equal in efficiency.

From the foregoing it is manifest that I entirely avoid the difficulties and defects incident to the use of the ordinary neutral relay.

It is manifest that with an apparatus constructed as shown and described herein there will be no breaks in the signals from the transmitting device. When the "B" key is worked alone the contacts of one relay of the double relay open and record signals. When the "A" key is depressed and the "B" key worked the A-key relay closes, or goes out of operation, and the signals are received on the "B" receiving relay. If, while the B-key is held down to record a dash, for example, and the "A" key is worked the armatures of the coils of the double relay reverse simultaneously and there is no break in the signal.

What I claim is:

1. A quadruplex telegraph system comprising means for transmitting impulses of current of opposite polarity, means for increasing and decreasing said currents, a polarized relay responsive to the reversals of polarity of the normal current, electro-magnetic devices adapted to be operated by the increased current, one of said devices responding to current of one polarity and the other responding to current of opposite polarity, a signal means controlled by both of said electro-magnetic devices and means controlled by said devices for inducing a current through the coils thereof when the line current is broken, said induced current being opposite in polarity to the interrupted line current.

2. A quadruplex telegraph system comprising means for transmitting impulses of current of opposite polarity, means for increasing and decreasing said currents, a polarized relay responsive to the reversals of polarity of the normal current, electro-magnetic devices adapted to be operated by the increased current, one of said devices responding to current of one polarity and the other responding to current of opposite polarity, a signal means controlled by both of said electro-magnetic devices and a transformer and circuits therefor arranged to induce a current in the coils of the electro-magnetic devices when the line current is broken, said induced current being opposite in polarity to the interrupted line current.

3. A quadruplex telegraph system comprising means for transmitting to the line impulses of current of opposite polarity, means for increasing and decreasing said current, a polarized relay responsive to the changes in polarity of the normal working current, a pair of polarized relays responsive to the increased currents, one of said relays responding to current of one polarity and 10 the other responding to current of opposite polarity, a signal means controlled by both of said relays whereby said signal means will be operated by the increased current of either polarity, and means controlled by the 15 pair of polarized relays to induce a current through the coils thereof when the line current is broken, said induced current being opposite in polarity to the interrupted line current.
- 20 4. A telegraph system comprising means for transmitting to the line impulses of current of opposite polarity, means for increasing and decreasing said current, a pair of polarized relays responsive to the increased currents, one of said relays responding to current of one polarity and the other responding to current of opposite polarity, and means controlled by said pair of polarized relays to induce a current through the 25 coils of said relays when the line current is broken.
- 25 5. A telegraph system comprising means for transmitting to the line impulses of current of opposite polarity, means for increasing and decreasing said current, a pair of polarized relays responsive to the increased currents, one of said relays responding to current of one polarity and the other responding to current of opposite polarity, and means controlled by said pair of polarized relays to induce a current through the 30 coils of said relays when the line current is broken.
- 35 6. A telegraph system comprising means for transmitting to the line impulses of current of opposite polarity, means for increasing and decreasing said current, a pair of polarized relays responsive to the increased currents, one of said relays responding to current of one polarity and the other responding to current of opposite polarity, and means controlled by said pair of polarized relays to induce a current through the coils of said relays when the line current is broken, said induced current being opposite in polarity to the interrupted line current.
- 40 7. A receiving means for a telegraph system comprising a pair of polarized relays electrically connected together, an armature for each of said relays, the windings of said relays being opposite in character so that one will respond to a current impulse of one polarity and the other will respond to a current impulse of opposite polarity, a local signal means controlled by both of the armatures of the said relays, and means for inducing in the relays when the line current is broken, a current opposite in polarity to the interrupted line current.
- 45 8. A receiving means for a telegraph system comprising a pair of polarized relays electrically connected together, an armature for each of said relays, one of said relays responding to current of one polarity and the other responding to current of opposite polarity, a local signal means controlled by both of the armatures of the said relays, and means for supplying to the relay coils when the line current is broken a current opposite in polarity to the interrupted line current.
- 50 9. A receiving means for a telegraph system comprising a pair of polarized relays electrically connected together, one of said relays responding to current of one polarity and the other responding to current of opposite polarity, a local signal means controlled by both of the said relays, and means for supplying to the relays when the line current is broken a local current opposite in polarity to the interrupted line current.

one polarity and the other will respond to a current impulse of opposite polarity, a local signal means controlled by both of the armatures of the said relays, and means for inducing in the relays when the line current is broken, a current opposite in polarity to the interrupted line current.

7. A receiving means for a telegraph system comprising a pair of polarized relays electrically connected together, an armature for each of said relays, the windings of said relays being opposite in character so that one will respond to a current impulse of one polarity and the other will respond to a current impulse of opposite polarity, a local signal means controlled by both of the armatures of the said relays, and means for inducing in the relays when the line current is broken, a current opposite in polarity to the interrupted line current, said means consisting of a transformer controlled by said polarized relays.

8. A receiving means for a telegraph system comprising a pair of polarized relays electrically connected together, an armature for each of said relays, one of said relays responding to current of one polarity and the other responding to current of opposite polarity, a local signal means controlled by both of the armatures of the said relays, and means for supplying to the relay coils when the line current is broken a current opposite in polarity to the interrupted line current.

9. A receiving means for a telegraph system comprising a pair of polarized relays electrically connected together, one of said relays responding to current of one polarity and the other responding to current of opposite polarity, a local signal means controlled by both of the said relays, and means for supplying to the relays when the line current is broken a local current opposite in polarity to the interrupted line current.

In testimony whereof I hereunto affix my signature in the presence of two witnesses.
